UNITED STATES PATENT OFFICE.

JACOB M. OLINGER, OF SPRINGFIELD, OHIO.

GAS HEATING STOVES.

Application filed February 17, 1926. Serial No. 88,753.

My invention relates to improvements in gas heating stoves.

One of the objects of my invention is to provide a gas heating stove so arranged so as to permit of a more even distribution of the heat rays throughout the space to be heated; a more particular object in this connection being to provide an arrangement in which the heat elements are arranged in a curvilinear series extending partially about the stove, with the space in front of the heat elements free from obstructions, so that the rays of heat are radiated in radial planes extending from the sides of the stove as well as the front thereof; a further object in this connection being to arrange the heat elements that the elements at each end of the series of elements are located on the arc of a circle of smaller radius than that of the intermediate elements, so that the proper amount of heating area may be secured without unduly extending the heating elements forwardly, as would be necessary if the heat elements were arranged on a true circle, and at the same time imparting to the front of the stove a flattened appearance.

In the accompanying drawing:

Fig. 1 is a front elevation of a stove embodying my improvement.

Fig. 2 is a side elevation of the same.

Fig. 3 is a sectional view on the line 3—3 of Fig. 1.

Fig. 4 is a sectional view on the line 4—4 of Fig. 3.

Fig. 5 is a detailed plan view of the burner, mixing chamber and mixing valve.

Referring to the drawings, 1 represents the base of the stove of curved form. The rear edges of this base are connected to vertical standards 2 and the forward portion of the base is provided with a pair of supporting legs 3. Secured to the base 1 and by the standards, is a support for the heating elements. This support consists of a curved portion 5, concavo-convex in cross section, an inner projecting shelf 6, an intermediate shelf 7 and a rear cross bar 8. The intermediate shelf 7 forms a support for a series of heat elements 9, which are known as radiants, while the shelf 6 forms a sup-

port for a curved back wall 10 of fire-proof material. This back wall 10 has at its upper end an integrally formed overhanging portion 10', the forward edge of which is of curved form. The radiants 9 are formed of fire-proof material and are of a type well known in the art of gas heating stoves. These radiants are held in position by a flange 5' formed at the juncture of the portion 5 and shelf 7 and also by a groove 60 formed on the under side of the portion 10', as indicated in dotted lines 10''. The fire-back 10 is held in position by forming therein grooves 11, which grooves engage the inner projecting edges of the standards 2 as shown in Fig. 3. As clearly shown in Figs. 3 and 4 a jacket plate 20 of usual form is secured to the rear faces of the uprights 2, and by reason of the particular connection of the ends of the substantially semi-cylindrical fire-back 10, no portion of the fire-back contacts with the jacket plate, the space between the fire-back 10 and jacket plate 20 providing for circulation of air therebetween so the stove may be set close to a house wall without danger of setting fire to the same due to the heat radiating from the fire-back, when the stove is in use. A cap of ornamental appearance is laid on the overhanging portion 10' of the fire wall, the upper end of the jacket plate 20, and on the upper ends of the standards. The curves upon which the support, back wall and over-hanging portion are formed are such that the radiants at each end of the series 85 are located on the arc of a circle of smaller radius than that of the intermediate radiants.

The burner which I employ consists of a curved forwardly disposed chamber 12, a rear chamber 13, two hollow arms 14 connecting the two chambers, a hollow member 15 connected at its rear end with the chamber 13, and a fuel and air mixing valve 16 connected with the forward end of the member 15. The chambers 12 and 13 and the arms 14 are preferably integrally formed while the member 15 is bolted to the flanged open bottom of the chamber 13. The burner thus formed is connected with ears 17, pro-

jecting from the rear edge of the shelf 6, and is also fastened to the standards 2 and to the bosses formed on its rear side of the cross-bar 8. The chamber 12 is disposed 5 beneath the radiants 9 and is provided with a series of nozzles 18, one for each radiant, which are screwed into openings 18' in the upper wall of the chamber 12. It will be noted that the passage in the member 10 15 diverges toward the mixing chamber, while the passages in the members 14 converged from the chamber 13 to the chamber 12. This allows the air and the gas to enter the mixing chamber in an expanded condition to secure a more thorough mixture, and to be then again contracted before entering the burner chamber 12 to give it the proper density for efficient combustion.

By the construction described it will be 20 seen that I have provided a heating stove which, upon being placed in a fire place or near one wall of a room, will radiate the rays of heat in all directions in the room, thus maintaining more nearly a uniform 25 temperature in all parts of the room than can be obtained by the usual type of gas heating stoves. It will be noticed that the frame or supporting members of the stove are so arranged that there will be no ob- 30 structing parts in front of the radiants, particularly those radiants at the extreme ends of the series, so that there will be no inter- 35 ference with the radiation of the heat rays from one end of the series of radiants to the other. The disposition of the end radiants on short arcs and the intermediate radiants on a comparatively long arc also provides an arrangement which has ade- 40 quate heating surface without unduly ex- tending the heating surface forwardly, as would necessarily be the case if the radiants were arranged on a true circle, and this 45 arrangement also gives a more flattened or straight effect to the forward portions of the heating surface.

Having thus described my invention, I claim:

1. In a gas heating stove, a supporting frame open at the front, and a series of exposed heat elements arranged in the open front of said stove in a curvilinear series, so as to extend across the front and about part at least of the sides of said stove, the elements at each end of the series of elements being arranged on the arc of a circle of 50 shorter radius than that of the intermediate elements.

2. In a gas heating stove, an open front supporting frame, a curved fire back sup- 60 ported by said frame, and a series of exposed heating elements arranged in a curved line in front of said back, so as to extend only across the front and at least part of the sides of the stove, the elements at each end of the 65 series of elements being arranged on the arc

of a circle of shorter radius than that of the intermediate elements.

3. In a gas heating stove, a supporting frame open at the front including a perpendicular standard at each side of the rear thereof, a series of exposed heating elements arranged in the open front of said stove in a curvilinear series so as to extend across the front and about part at least of the sides of said stove, the elements at each end of the series of elements being arranged on the arc of a circle of shorter radius than that of the intermediate elements, all of said elements being arranged in vertical planes forward of the vertical planes of the front faces of said standards. 70 75 80

4. In a gas heating stove, a supporting base, uprights at the rear corners of the base, said uprights having at their faces inwardly projecting flanges; a jacket plate 85 connecting the rear faces of the uprights; a fire-back supported on said base in front of the jacket plate, each end of said fire-back having a groove receiving the flange of its adjacent upright whereby the fire-back is 90 entirely spaced from the jacket plate; and a series of heating elements mounted in the outer face of the fire-back. 95

5. In a gas heating stove, a supporting base, uprights at the rear corners of the base, said uprights being of substantially 100 channelled cross-section with the bosoms of the channels opening inwardly; a jacket plate connecting the rear legs of the channels; a fire-back supported on said base in front of the jacket plate, each end of said fire-back having a groove receiving the end of the outer leg of its adjacent channel whereby the fire-back is entirely spaced from the jacket plate; and a series of heating elements mounted in the outer face of the fire-back. 105

6. In a gas heating stove, a substantially semi-circular supporting base, uprights at the rear corners of the base, said uprights having at their outer faces inwardly projecting flanges; a jacket plate connecting the rear faces of the uprights; a substantially semi-cylindrical fire-back supported on said base in front of the jacket plate, each end of 110 said fire-back having a groove receiving the flange of its adjacent upright whereby the fire-back is entirely spaced from the jacket plate to form an air space therebetween; a series of heating elements mounted in the outer face of the fire-back; and a cap seated upon the upper ends of the fire-back, up- 115 rights, and jacket plate. 120

7. In a gas heating stove, a substantially semi-circular supporting base, uprights at 125 the rear corners of the base, said uprights being of substantially channelled cross-section with the bosoms of the channels opening inwardly; a jacket plate connecting the rear legs of the channels; a substantially semi- 130

cylindrical fire-back supported on said base in front of the jacket plate, each end of said fire-back having a groove receiving the end of the outer leg of its adjacent channel 5 whereby the fire-back is entirely spaced from the jacket plate to form an air space therebetween; a series of heating elements

mounted in the outer face of the fire-back; and a cap seated upon the upper ends of the fire-back, uprights and jacket plate. ¹⁰

In testimony whereof, I have hereunto set my hand this 15th day of February, 1926.

JACOB M. OLINGER.
